UNITED STATES PATENT OFFICE

ALBERT E. GARBUT, OF WINNIPEG, DONALD COCHRANE, OF ST. BONIFACE, AND JOHN E. WATKINS, OF WINNIPEG, MANITOBA, CANADA, ASSIGNORS TO WINNIPEG BRASS LIMITED, OF WINNIPEG, CANADA, A CORPORATION OF MANITOBA, CANADA

ANNUNCIATOR-RECEIVING CASING

Application filed June 18, 1928. Serial No. 286,180.

The invention relates to improvements in annunciator receiving casings and an object of the invention is to provide a casing for mounting such as on the forward end of a street car and designed to receive and protect a route indicating annunciator, the casing being supplied with a window through which the annunciator is visible and also with guides to slidably receive the annunciator 5 when it moves up into place.

10 A further object of the invention is to provide a casing for receiving and protecting the annunciator and means suspending the annunciator in the working position, said 15 means being arranged so that the annunciator can be easily and quickly removed from the casing and without in any way interfering with the casing or the illuminating means provided within the casing for illuminating the annunciator.

15 A further object is to provide a receiving casing for the annunciator which will have a neat and pleasing appearance both from the exterior and interior of the car and to arrange the parts so that the annunciator can 20 be removed by the motorman without requiring to leave the car vestibule and without requiring any tools to do the work and further to provide means whereby the motorman can readily see the route number displayed by the annunciator when the same 25 is in working position within the casing.

30 A further object is to construct the casing with guides to prevent lateral sway of the 35 contained annunciator.

With the above more important and other minor objects in view which will become more apparent as the description proceeds, the invention consists essentially in the arrangement and construction of parts herein- 40 after more particularly described, reference being had to the accompanying drawing, in which:—

Fig. 1 is a vertical sectional view through 45 the forward end of a street car and through the annunciator protective casing and showing the annunciator and the illuminating lamp inside elevation and the annunciator in its working position within the casing.

50 Fig. 2 is a view similar to Figure 1, the

closure plate being shown in end elevation and the annunciator being shown as partially withdrawn from the protective casing.

Fig. 3 is a vertical cross sectional view 55 through the casing at 3—3' Figure 2, the annunciator contained therein being shown in front elevation.

Fig. 4 is a perspective view of the closure plate, brackets and other associated parts.

In the drawing like characters of reference 60 indicate corresponding parts in the several figures.

We may here explain that the structural arrangement of the annunciator herein shown forms a separate invention and is shown and 65 described in detail in a co-pending application filed by us on the 18th day of June, 1928 under Serial No. 286,181.

The annunciator presents a box like casing 1 having front and rear windows 2 and 3 70 and endless belts indicated at 4 and 5 Figure 3 contained within the casing, the belts being provided each with a series of numbers and being adapted when wound and set to indicate the route number of the car. In 75 Figure 3, the route number is indicated as 38. Each winding belt is selectively controlled by a winding crank 6 located at the lower end of a tube 7 extending downwardly from each end of the box, the cranks 6 being within convenient range of the motorman. A combination closure and attaching plate 8 is permanently secured to the bottom of the box and extends beyond the ends thereof and is provided at the ends with holes 9 and 10 80 utilized for suspending the annunciator in working position.

We have not herein deemed it necessary to give any further description of the annunciator as its detail structure forms no part of the present invention other than that the plate 8 is utilized to suspend the annunciator in working position and coacts with parts later described for such purpose.

A route annunciator such as described is 95 displayed on a prominent part of the street car so that it can be readily seen by pedestrians and experience seems to indicate that the most desirable place is on the car roof directly overlying the motorman's vestibule. 100

5 We have found that it is very desirable to house the annunciator so that it is protected from the weather, dust and dirt and whilst not interfering with the visibility of the annunciator and to this end, we have provided a receiving casing or housing indicated generally by the reference numeral 11 and mounted on the roof of the car.

10 The housing is herein shown as formed from sheet metal and having the top, back and ends closed, the bottom open and the front provided with a window 11', the window being of sufficient area so that one can clearly see a route number displayed by the 15 contained annunciator. The housing or casing 11 is provided at the bottom with a circumscribing outstanding flange 12 which can be permanently nailed or screwed to the roof of the car and as it is desired to make the same 20 dust proof, a strip of canvas, felt or other yielding material can be placed between the flange and the car roof prior to nailing as will be readily understood.

25 The roof boards of the car are cut away to provide a substantially rectangular entrance opening 13 to the interior of the casing 11 from the vestibule and a passage 14 through the roof centrally of the length of the rectangular opening 13. The opening 13 is forwardly positioned in regard to the casing 11 and is of such area that it will freely admit the box like casing 1 of the annunciator. Adjoining the ends of the opening, we locate 30 a pair of spaced, parallel, horizontally disposed, rearwardly extending brackets 15 and 16 in the form of bars having their forward ends down turned and bolted as indicated at 35 17 to one of the cross rafters 18 of the roof and their rearward ends up turned and bolted or screwed as indicated at 19 to another 40 of the roof rafters 20.

45 These brackets are spaced so that the annunciator casing 1 can be passed upwardly into the casing 11 there between and when 50 the annunciator is in its uppermost position, the plate 8 thereof is adapted to engage with and be stopped by said brackets. The brackets both carry downwardly extending bolts 21 adapted to pass through the openings 9 and 55 10 of the plate and the bolts are each fitted with a winged nut 22 so that when the plate has been raised and the bolts 21 passed through the openings 9 and 10 of the plate, the annunciator can be suspended in its working 60 position by applying the nuts 22 and tightening the same up to jam the ends of the plate between the nuts and the brackets. The window 2 of the annunciator in its working position will be directly to the rear of the 65 window 11' and obviously the casing 11 must be high enough so that it will in no way interfere with the passing of the annunciator to its final position.

65 The end walls of the casing 11 are each provided with a guide 23 presenting opposing

vertically extending inturned flanges 24 and 25. The ends of the up moving annunciator are adapted to be received between and guided by the flanges and when the annunciator is in its final or uppermost position, the flanges prevent forward or back sway of the annunciator and co-operate with the bolts 21 and nuts 22 to hold the annunciator firmly in place.

70 The area to the rear of the plate 8 of the annunciator when in its up position, is closed by a closure plate 26 which is provided at the rear edge with an up turned flange 27 fastened by the screws 19 to the roof rafter and at the ends with L-shaped flanges 28 and 29 fastened by screws or nails 30 to the roof boards. The closure plate 26 is supplied with a peep opening 31 normally closed by a sliding gate 32, the gate being fitted with a finger piece 33 so that it can be readily opened and closed by the motorman.

75 The casing 11 supports centrally of its length and on the top side, an electric light socket 34 in which is screw threaded the customary electric lamp 35. This lamp is utilized to illuminate the annunciator when desired and as the annunciator is provided as hereinbefore stated with a front window 2 and a rear window 3, it is quite easy for the pedestrian to see the route number of the annunciator through the window 11' when the same is illuminated such as at night by the 80 electric lamp 35.

85 The feed wires 36 and 37 lead in the usual manner from the light socket, pass downwardly through the passage 14 and then transversely of the car in a location between the plate 26 and the roof and finally pass out through the opening 38 appearing above the bracket 16 and adjoining the forward end 90 of the flange 28 and are connected with a 95 source of current.

100 According to the above arrangement when one wishes to remove the annunciator for inspection, cleaning or other purposes, the 105 illuminating light or wires leading thereto are in no way disturbed. The housing 11 effectively protects the annunciator from the weather, dust and dirt and also prevents rain, 110 snow, dust or dirt from entering the car and 115 in no way interferes with the visibility of the annunciator. Further the motorman or other responsible party can bodily remove the annunciator by simply undoing the nuts and 120 sliding it down out of the casing 11 and such 125 in no way interferes with the casing 11, the illuminating light or wires leading thereto.

130 It is a simple matter to reinsert the annunciator as it is only necessary to pass it through the opening 13 and shove it up in the guides 23 until the plate 8 is arrested by the brackets. Then by applying the nuts 22 and tightening up, the work of resetting is completed.

If the motorman desires at any time to re-

plenish a lamp or to see the numbers displayed on the annunciator, such can be readily done by opening the gate 32.

What we claim as our invention is—

5 1. The combination with the roof of a car, of an annunciator receiving and protecting casing permanently mounted on the roof and provided at the forward side with a window, there being an entrance opening through the 10 car roof to the interior of the casing, an annunciator vertically slideable to housed position within the casing through the opening aforesaid and visible in said housed position through the window and means operable 15 from the interior of the car for releasably fastening the base of the annunciator to the car roof.

2. The combination with the roof of a car, of an annunciator receiving and protecting 20 casing permanently mounted on the roof of the car and provided with a forward window, there being an entrance opening provided in the roof and opening to the casing, a box like annunciator adapted to be passed vertically through the opening into housed position within the casing and visible in housed position through the window aforesaid, guides carried by the ends of the casing and guiding the annunciator as it is being passed 30 into the casing and preventing side sway of the entered annunciator and means operable from the interior of the car for releasably supporting the entered annunciator.

3. The combination with the roof of a car, 35 of an annunciator receiving and protecting casing permanently mounted on the roof of the car and provided with a forward window, there being an entrance opening provided in the roof and opening to the casing, a box like annunciator adapted to be passed vertically through the opening into housed position within the casing and visible in housed position through the window aforesaid, guides carried by the ends of the casing and guiding the annunciator as it is being passed 40 into the casing and preventing side sway of the entered annunciator, supporting members extending from the ends of the annunciator base, bolts carried by the roof of the car and adapted to pass through suitable 45 openings provided in said supporting members and nuts mounted on the bolts and engaging said supporting members.

4. The combination with the roof of a car, 55 of an annunciator receiving and protecting casing permanently mounted on the roof of the car and provided at the front side with a window, an annunciator adapted to be passed through a suitable opening provided in the 60 roof of the car into the forepart of the casing, said inserted annunciator being visible through the window, a pair of spaced brackets permanently secured to the under side of the car roof, said brackets being at the ends 65 of the annunciator in its entered position, a

plate permanently secured to the base of the annunciator and engageable with the under sides of the brackets in the entered position of the annunciator and attaching bolts carried by the brackets and passing through suitable openings provided in the ends of the plate and detachably supporting the annunciator.

5. The combination with the roof of a car, 70 of an annunciator receiving and protecting casing permanently mounted on the roof of the car and provided at the front side with a window, an annunciator adapted to be passed through a suitable opening provided in the roof of the car into the forepart of the 75 casing, said inserted annunciator being visible through the window, a pair of spaced brackets permanently secured to the under side of the car roof, said brackets being at the ends of the annunciator in its entered position, a plate permanently secured to the base of the annunciator and engageable with the under sides of the brackets in the entered position of the annunciator, attaching bolts carried by the brackets and passing through suitable 80 openings provided in the ends of the plate and detachably supporting the annunciator and a stationary closure plate carried by the roof of the car to the rear of the latter plate and provided with a normally closed 85 peep opening.

Signed at Winnipeg this 16th day of April, 1928.
